UNITED STATES PATENT OFFICE.

EDWIN GUSTAFSON, OF CHICAGO, ILLINOIS, ASSIGNOR TO THE PALTRIDGE METAL EQUIPMENT COMPANY, OF CHICAGO, ILLINOIS, A CORPORATION OF ILLINOIS.

METAL DOOR.

1,153,549.

Specification of Letters Patent. Patented Sept. 14, 1915.

Application filed April 25, 1914. Serial No. 834,464.

To all whom it may concern:

Be it known that I, EDWIN GUSTAFSON, a subject of the King of Sweden, residing at Chicago, in the county of Cook and State 5 of Illinois, have invented certain new and useful Improvements in Metal Doors, of which the following is a specification.

My invention relates to sheet metal door and window frame construction.

10 One of the general objects of my invention is to provide a new and improved hollow rectangular frame, suitable for sheet metal doors, or windows, having a rectangular cross section and preferably presenting 15 substantially continuous, longitudinal, inwardly-facing slots, in each of the members, wherein to insert the attaching means for holding the molding and retaining the panels, of metal or glass, in place, without 20 providing other openings in the structure for the introduction of such parts.

Another and more specific object of my invention is to provide means for joining the mitered ends of the molding, to hold 25 relative parts thereof in common planes, so as to prevent them from tilting, or cocking up at their edges. And still another object I have in view is to provide convenient means for adjustably moving the panel and 30 molding locking strips by means projecting through the body part or frame of the door, whereby the parts to be assembled, within the frame of the structure, may be taken out and replaced by a novice without the necessity 35 of inserting a special tool within the frame, or providing an additional opening to be subsequently closed, for accomplishing this result.

Other, further and more specific objects 40 of my invention will become readily apparent to persons skilled in the art, from a consideration of the following description when taken in conjunction with the drawings, wherein—

45 Figure 1 is an elevation of a door, or sash. Fig. 2 is a transverse section, taken on line 2—2 of Fig. 1. Fig. 3 is a transverse section, taken on line 3—3 of Fig. 1. Fig. 4 is a section taken on line 4—4 of Fig. 3. Fig. 50 5 is a transverse section, similar to Fig. 3, of a modified form of construction. Fig. 6 is a similar view of another modified form of construction. Fig. 7 is a sectional view taken on line 7—7 of Fig. 5. Fig. 8 is a 55 sectional view taken on line 8—8 of Fig. 6.

Fig. 9 is a section taken on line 9—9 of Fig. 1. Fig. 10 is a perspective view of a broken away corner of the frame. Fig. 11 is an elevation showing the manner of joining the molding members at a mitered corner. Fig. 12 is the retaining clip for holding the mitered parts in their true position, while they are being locked in the panel. Fig. 13 is a clip, insertible within the molding, and forming one of the members for locking 65 same in place within the frame.

In all the views the same reference characters are employed to indicate similar parts.

The stiles 15—15 and the end rails 16—16 70 are substantially of the same cross section, each being provided with a wall 15^a and two side walls 15^b—15^b. One form of the structure shown in Fig. 5 contains only these three walls and this is especially true where 75 the beading extends laterally beyond the walls 15^b as in Fig. 5. Where the outer surface of the molding comes substantially flush with the walls 15^b, the end wall 15^c is outwardly deflected, as at 15^d to provide 80 a shoulder or rest for the molding as clearly shown in Figs. 2, 3, and 10, while in Fig. 6, in which the molding is applied only on one side of the frame, one of the walls 15^b, extends forwardly, as at 15^e, and bends back 85 upon itself to form a channel for a locking strip, as at 15^f, as will be hereinafter more fully described. The stiles 15—15 and the end rails 16—16 are mitered together, as at 17. Inner plates 18 and 19 may be provided 90 for this purpose, the walls being preferably spot welded to these plates, in initially putting the frame members together.

The space or channel, between the confronting wall portions 15^a—15^d preferably 95 extends longitudinally of the respective members, and provides an opening through which reinforcements may be inserted for the purpose of attaching the necessary hardware to the frame, such as the lock, hinges 100 and the like.

Locking strips 20, 20^a and 20^b, as the case may be, extend for a considerable length of each of the members 15 and 16 and in each case the locking strips are adapted to fit 105 neatly within the longitudinal openings provided in confronting side walls of said frame structure.

The locking strips 20, 20^a as shown, are channel shaped, each having a vertical por- 110

tion and two laterally deflected confronting portions, bent in the same direction to provide the channel, while the locking strip 20^b, owing to the changed construction of the frame members, has one of its longitudinal sides bent in the same direction as the other form of strip, but its other side is bent in the opposite direction, as at 15^d, resembling a Z-shape instead of a U-shape and lies between the wall 15^e and 15^f, as shown in Fig. 6. Each of the locking strips is provided, at selected intervals with slots, or perforations 21, in their side members.

A panel 22, which may be either glass, or other suitable material, is to be placed within the area surrounded by the frame, and held therein by means of molding strips 23, which may be placed on either or both sides of said panel. The molding strip frame being co-extensive with the inner opening of the frame adapted to be supported by the frame. The strips may be made of a front wall 24 bent into an ogee mold with a beading 25, and a rear wall 26, and another beading 27 at its outer marginal edge. The bead 25 is again bent upon itself, as at 28, preferably to form a surface that may rest upon the shoulder provided by the wall 15^a of the frame member. Adjacent strips of molding 23—23 are mitered at their edges, as at 23^a—23^a to make a joint between said molding pieces, corresponding with the preferably mitered joints between the end and side members of the frame. To prevent tilting, or cocking up, of the molding members thus joined, I prefer to employ an angle piece 29, made of sheet metal, which fits snugly within the interior of the hollow molding members, being bent or deflected in its miter plane in such manner as to hold the parts of the molding, at the joint, in perfect alinement, thus preventing any relative displacement thereof. The angle piece 29 may be spot welded, or otherwise secured to either of the molding members 23, or to both, if desired. It will, however, perform its necessary and required function without being positively united or connected to either of the molding members. The angle piece 29 fits tightly in the corners provided between the walls 26 and 27, and the diagonal corners provided by the bead 25 of the molding, and the parts 29—29' are so bent or deflected with reference to each other as to conform to the proper angularity of the molded pieces. A locking clip 30 of which there may be any desired number are in like manner placed within the hollow portion of the molding 23, in generally the same situation. They are each adjustable, longitudinally of the molding, so as to be brought to register with the openings 31 provided in the wall-members 15^a—15^a, of the stiles 15—15 and the end rails 16—16. Each of the clips 30 is pro-

vided with a locking lug 30' that is preferably punched from the body portion of the strip and bent at right angles as clearly shown in Fig. 13 and it is this locking lug that must register with the opening 31 provided in the frame member. The clips 30, may be moved along the interior of the molding to the selected position until they will freely enter the openings referred to, at which time they will project through similar openings 21 made at equal intervals in the side walls of the locking strips 20—20^a or 20^b, as the case may be. As many such openings 31, as may be desired, may be placed through the side and end members of the frame, and a corresponding number of openings 21 may be made through the locking strips 20, and an equal number of locking clips 30 will be necessary to be placed in the molding strips 23.

Secured at one end, to each of the locking strips 20—20^a—20^b is a strip extension 32, fastened to said strip by riveting, welding, or the like, as at 33. Each strip 32, is twisted a quarter turn, as at 34, so that these strips may pass each other to be conveniently separated and independently adjusted without relative interference. Each of the strips is bent at its end at an angle, as at 35, the bent end being perforated and threaded for an adjusting screw 36, which passes through the wall of one of the frame members, as shown clearly at 37, in Fig. 1. When the screw 36 is rotated it causes the locking strip to be drawn toward the outer wall of the frame member, in the process of locking the molding strip to the frame member thereby securing the molding frame and panel in proper positions.

To assemble the parts in the frame, composed of the members 15 and 16 it will be understood that the frame is first made complete, the joining ends of the frame members being suitably connected together, as by welding, or otherwise, and by the use of a mitered or square joint, as best suited for the purpose.

After the frame has been completed the inserts, necessary for attachment of the required hardware to the frame, such as locks, hinges and the like may be passed through the channel openings made in the side walls 15^e of the frame, after which the locking strips 20 are placed in the openings, which substantially closes the openings. The locking strips are moved longitudinally of the frame members until the slots 21 of the locking strips register with the slots 31 made in the portion 15^a of the side wall 15^e of said members. There may be as many of these registering openings in the respective members as may be desired for properly holding the molding in place. The locking clips 30 are then placed inside of the molding strips 23 so that the tongues 30' thereof,

will project beyond the edge of the wall 26, of the molding strip, as clearly shown in Fig. 3. The clips 30 are longitudinally adjustable, within the molding strip 23, and should be moved in said molding strip, until they occupy positions registering with the slots 21 and 31 of the respective locking strips and frame members, so that the tongues 30' may be easily passed through said perforations when the molding strips are placed in position. Before placing the molding strips 23 within the frame, the respective strips are relatively placed so that their adjoining ends produce a proper miter joint, as shown in Fig. 10, and so that the angular piece 29-29' will enter each of the adjacent molding strips just as the locking clips 30 are secured within such strips.

The inner frame, which is made by the joining of the respective molding members, is placed within the main frame on one or both sides of the panel so that the locking tongues 30' of the clips 30 will pass through the registering slots or openings, heretofore referred to, and the locking strip extensions 32 are extended toward the respective walls of the frame. The bent portion 35 on the end of the extension 32 is provided with a screw threaded hole and a screw 36, inserted through the opening 37 in the frame must be entered in this hole.

To lock the molding frame in place the screw 36 is turned, thus drawing the locking strip longitudinally so that the perforations 21 of the strip no longer register with the perforations 31, as shown in Fig. 4, and the body portion of the locking strip, beyond said perforations passes under the tongues 30' of the locking clip 30, thereby wedging the parts together and preventing removal of the panel and molding.

After the molding has thus been applied to one side of the frame, the panel 22 is then placed on the surfaces or shoulders 26, of the molding, and the molding frame on the opposite side of the panel is placed in position in a similar manner, the screws 36 being turned until the molding on each side of the panel is securely fastened to the main frame.

The strips 23 of the molding frame may be removed from the main frame by turning the screws 36 in the opposite direction and by driving on the end of the screws thereby longitudinally moving the locking strip back into its former position of registration of slots 21 with the slots 31 in the frame member, at which time the molding frame may be lifted from its place and the panel 22 removed.

While I have herein shown a single embodiment of my invention for the purpose of clear disclosure it is evident that consider-

able changes may be made in the relative positions and configuration of the parts 65 within the meaning of the appended claims.

Having described my invention, what I claim is:—

1. A device of the character described comprising a hollow, rectangular frame; a panel 70 for inclusion therein; molding strips overlying said panel carrying lugs; longitudinally movable locking strips provided with coacting locking members within said frame; and screws taking through the edge walls of 75 the frame and engaging said strips to longitudinally move them into locking position to hold the molding and panel in place.

2. A device of the character described comprising a hollow, rectangular frame, provided with slots in its inner edge; a panel 80 for inclusion within said frame; molding strips overlying said panel; longitudinally adjustable lugs within said molding strips; longitudinally movable strips provided with 85 slots coacting and registering with slots within said frame; and screws taking through the outer edge walls of the frame and engaging said strips to move them into locking engagement with said lugs and out 90 of register with the slots in said frame.

3. A device of the character described comprising a hollow, rectangular frame, provided with a substantially continuous opening in its confronting walls and having 95 transverse slots in its walls near said opening; longitudinally movable strips substantially closing said opening having registering slots in its walls; a molding frame provided with tongues projecting through 100 said openings and means movable from the outside of said frame to move the strips to engage said tongues and lock the molding frame.

4. In a device of the character described, 105 the combination of a hollow, rectangular frame providing a shoulder for seating a molding by deflecting part of its inner wall inwardly, and having slots through the walls of the shoulder parts; a molding seated on 110 said shoulder; a strip having slots registering with the slots in said shoulder; a clip longitudinally adjustable within said molding having locking lugs for projection through said slots when the latter are in 115 register and a screw passing through the outer edge wall of the frame and engaging said strip to move the latter longitudinally to lock the molding in the frame.

In testimony whereof I hereunto set my 120 hand in the presence of two subscribing witnesses.

EDWIN GUSTAFSON.

In the presence of—

FONÉE BAIN,
MARY F. ALLEN.
